UNITED STATES PATENT OFFICE.

THOMAS W. JOHNS, OF BROOKLYN, NEW YORK.

TYPOGRAPHICAL MACHINE.

1,318,878.

Patented Oct. 14, 1919.

Application filed August 16, 1918. Serial No. 250,182.

To all whom it may concern:

Be it known that I, THOMAS W. JOHNS, a citizen of the United States, residing at Brooklyn, in the county of Kings and State 5 of New York, have invented new and useful Improvements in Typographical Machines, of which the following is a specification.

This invention relates to improvements in typographical machines and more especially 10 to those of the linotype class wherein the matrices from which the type slugs are cast are stored in one or more magazines occupying an inclined position on the machine and from which the matrices are delivered under 15 the control of suitable escapements actuated by a keyboard.

The primary object of the invention is to provide novel and improved means for mounting a plurality of magazines in the 20 machine whereby one or another of such magazines may be easily and quickly brought into position to deliver matrices therefrom without interrupting or otherwise disturbing the distribution of matrices re- 25 turning to the magazine previously in use, thus enabling the operator to change the magazines in the machine without being delayed until the distribution of matrices re- turning to the magazine previously in use 30 has been completed.

Other objects of the invention are to pro- 35 vide improved means for shifting the mag- azines to bring one or another thereof into position for use, and to provide a plural 40 magazine machine wherein the distributing mechanism and the magazine entrances for guiding the matrices from the distributing mechanism into the respective magazines are in fixed relation to one another and the 45 magazines thus enable distribution of the matrices to the different magazines to con- tinue without interruption during and after a shift has been made to carry one mag- azine out of the position for use and to bring 50 another magazine into such position.

To these and other ends, the invention 55 consists in certain improvements, and com- binations and arrangements of parts, all as will be hereinafter more fully described, the 50 novel features being pointed out partic- ularly in the claims at the end of the speci- 55 cation.

In the accompanying drawings:

Figure 1 is a side elevation of the upper 55 portion of a typographical machine con-

structed in accordance with the present in- 60 vention, two magazines being shown and the upper magazine being in position for use.

Fig. 2 is a view similar to Fig. 1 but show- 65 ing the lower magazine in position for use.

Fig. 3 is a detail sectional view of the 70 lower end of one of the matrix magazines showing the escapements controlling the de- livery of matrices therefrom.

Fig. 4 is a rear elevation, partly in sec- 75 tion, of the magazines, their carrying frame, and the distributing mechanism carried by such frame.

Fig. 5 is a view similar to Fig. 2, showing 80 the magazines elevated to a height to per- mit removal of the lower magazine from its frame, and also showing means for driving the distributors for the upper and lower magazines.

Fig. 6 is a rear elevation of the entrance 75 ends of the upper and lower distributors, on an enlarged scale, showing means for sep- arating the matrices belonging respectively 80 to the upper and lower magazines and the chute for conveying the matrices to the lower distributor.

Fig. 7 represents a section on the line 7—7 85 of Fig. 6, showing a matrix belonging to the lower magazine in the act of dropping from the distributor bar of the upper dis- tributer.

Fig. 8 represents a section on the line 8—8 of Fig. 6, showing a matrix belonging to the upper magazine hanging on the dis- tributer bar of the upper distributor. 90

Similar parts are designated by the same reference characters in the several views.

The present invention is applicable to 95 typographical machines generally, although it is particularly applicable to those of the linotype class wherein the magazines containing the matrices occupy a forwardly and downwardly inclined position in the machine, the matrices being delivered from the lower or forward end of the magazine in use 100 under the control of keyboard-actuated es- capements, and the matrices after a cast has been made therefrom are returned to the upper rear end of the magazine through the operation of a distributing mechanism. The preferred embodiment of the invention is 105 shown in the accompanying drawings and will be hereinafter described in detail. It is to be understood, however, that the invention is not restricted to the precise construc- 110

tion shown as equivalent constructions are contemplated and will be included within the scope of the claims.

In the present instance, 1 designates the upper portion of the keyboard frame of a machine of the linotype class, this keyboard frame being fixed to and forming a part of the main frame and serving to guide the row of vertically movable reeds 2, the latter being actuated in any suitable way as, for example, by the usual keyboard mechanism as employed in machines of this class. 3 designates the upper portion of the assembler chute through which the matrices delivered from the lower forward end of the magazine in use descend on their way to the assembling mechanism, the assembling mechanism being of any suitable construction, such for example as that commonly used in machines of the linotype class. 4-4 designate the brackets or arms which are fixed to the main frame and are similar to or correspond with the distributor brackets commonly used in machines of the linotype class.

The present invention provides means for mounting a plurality of matrix magazines in the machine and for shifting such magazines to bring one or another of such magazines into position for use. As shown in the present instance, two magazines M and M' are accommodated in the machine, these magazines being preferably of the usual construction having opposed sets of grooves in their top and bottom plates to receive the edges of the matrices, and escapements 5 and 6 are provided at the lower end of each magazine to control the delivery of matrices therefrom. Escapements of different kinds may be used, the double pallet escapement shown as an example in the present instance comprising the member 5 which is pivoted at the lower side of the magazine on the axis 7 and is adapted to control the discharge of the lowermost matrix from the magazine, and the member 6 being pivoted to the under side of the magazine at 8 and operating to control the advance of the following or next lowest matrix in the magazine. A spring 9 operates to normally hold the escapement members in the position shown in Fig. 1, the lowermost matrix in the magazine being then in readiness for delivery but being retained by the escapement member 5. Each member 5 of the various escapements is adapted to be actuated by a corresponding reed 2 of the keyboard mechanism in the usual way to effect the delivery of the selected matrix from the respective channel in the magazine. These magazines, according to the present invention, are mounted in a magazine frame 10. Preferably, and as shown, the magazines are mounted removably in this frame, the frame having a pair of upper seats 11 and 12 in which cross-bars 13 and 14 are mounted to rest on the under side of the upper magazine.

adapted to rest, and the frame also having lower seats 13 and 14 in which cross-bars on the lower magazine are adapted to rest. The magazines are preferably so mounted in the frame 10 as to bring the lower or matrix delivery ends thereof into relatively close relation and to bring their upper or matrix-receiving ends into a more widely spaced relation in order to reduce to a minimum the extent of movement of the magazines necessary to bring one or another of the magazines into position for use and to accommodate the matrix distributing mechanism at the upper ends of the magazines. The frame 10 is preferably provided with stops or seats 15 and 16 which are adapted to coöperate respectively with the corner 17 of the frame 1 when the frame 10 is in its lower and upper positions corresponding to the operative positions of the two magazines.

According to the present invention, a duplex distributing mechanism is provided for returning the matrices to the appropriate channels of the respective magazines, and this distributing mechanism is carried by 90 and shiftable with the frame 10 and hence its relation to the magazines on the frame 10 is not disturbed during the shifting movements of the frame 10 to bring one or another of the magazines thereon into position for use. As shown, the duplex distributing mechanism comprises an upper distributor 18 for the upper magazine M, this upper distributor comprising a combination rail or bar 19 and conveyer screws 20 which may be of the construction commonly used in machines of the linotype class, and the distributor 21 for the lower magazine M' comprises a similar combination rail or bar 22 and conveyer screws 23. The combination rails or bars 19 and 22 and also the conveyer screws 20 and 23 of the two distributors are mounted in fixed relation on the upper portion of the frame 10, and channel entrances 24 and 25 which also occupy fixed positions on the magazine-carrying frame 10 are interposed between the distributors and the respective magazines M and M' and they serve to guide the matrices from the distributors into the appropriate channels of the respective magazines. The distributor box 26, which in machines of the linotype class receives the matrices from the second elevator, is also carried by the frame 10 and is mounted in fixed relation thereon. By this construction, the matrices belonging to both the upper and the lower magazines may all be returned to the distributor box, but suitable means is used for distinguishing between the matrices belonging to the upper magazine and those belonging to the lower magazine. Preferably, the combination rails or bars 19 and 22 for the upper and lower magazines are of duplicate construction in respect to the ribs thereon which coöperate with the 130

teeth in the upper edge of the matrices, but the end of the upper combination bar 19 which projects into the distributor box is cut away, except for its lowermost rib 27, this lowermost rib 27 extending to the distributor-box rails 28. The matrices belonging to the upper magazine are provided with an additional pair of teeth 29 which are adapted to fit upon the lowermost rib 27 of the upper combination rail 19, while the matrices belonging to the lower magazine are formed without these teeth 29. In consequence, matrices having the additional teeth 29 will be supported by the engagement of these teeth with the lowermost rib 27 of the upper combination rail 19 as such matrices enter the distributor, and such matrices as they proceed will become engaged in the usual way upon the upper combination rail, while the matrices belonging to the lower combination rail and which are formed without the additional teeth 29 (see Fig. 7) will not be supported by the rib 27 as such matrices enter the distributor, in consequence of which such matrices will drop from the distributor through a suitable chute 30 to the entrance end of the combination rail 22 of the lower distributor and will be engaged with said rail by suitable means, such as a matrix lifter 23^a similar to the matrix lifter 23^b of the upper distributor, these matrix lifters shown being similar to those commonly used in machines of this class for the same purpose. Distribution of the matrices to the different magazines may take place concurrently, the matrices belonging to the upper and lower magazines being separated or distinguished from one another by the extended rib 27 at the entrance to the upper distributor.

The present invention provides relatively simple and efficient means for shifting the magazine-carrying frame 10 to bring either of the magazines thereon into position for use. In the present instance, the upper portion of the frame 10 is supported by a shaft 31 the ends of which are journaled in the fixed arms or brackets 4, and this shaft is provided with a pair of eccentrics 32 which are rotatably fitted into the opposite sides of the magazine-carrying frame 10. When this frame 10 is in position to set either of the magazines thereon in its operative position, the eccentrics 32 are thrown downwardly into a substantially vertical position, as shown in Fig. 2, the shaft 31 being rotatable to throw the eccentrics 32 rearwardly to effect corresponding rearward movement of the magazine frame 10 and the magazines thereon preparatory to a shift of the magazines, as will be hereinafter described. The lower or forward portion of the magazine-carrying frame 10 is provided with a cross-bar 33 which connects the sides of the frame, and this cross-bar rests on a cam 34, the

latter being fixed on a shaft 35 which is journaled in relatively fixed brackets 35^a and is provided with an operating crank 36. The shaft 35 also has a crank 37 fixed thereto and this crank is connected by a link 38 to a crank 39, the latter crank being fixed to the shaft 31. The cam 34 is so shaped that when the shaft 35 occupies the position shown in Fig. 1, the cross-bar 33 resting on said cam will support the frame 10 at such a level as will position the upper magazine M in proper relation to the assembler chute and the reeds will coöperate with the escapement, and when the shaft 35 occupies the position shown in Fig. 2, the frame 10 will be placed at such a level as will bring the lower magazine M' into coöperative relation with the assembler chute and escapement actuating reeds.

The operation of changing the magazines in the machine to bring one or the other into use is as follows: Assuming the upper magazine M to be in use, as shown in Fig. 1, it is only necessary to swing the handle 36 in a rearward and downward direction from its position as shown in Fig. 1 into the position shown in Fig. 2. The rotation thus imparted to the shaft 35 pushes the link 38 rearwardly, thereby swinging the eccentrics 32 rearwardly, and by virtue of the engagement of these eccentrics in the sides of the magazine-carrying frame 10, the latter, together with the magazines thereon, is moved rearwardly, thus withdrawing the escapements of the upper magazine from above the reeds and also withdrawing the stop or seat 15 from the corner 17 of the stationary frame. Concurrently with the rearward shift of the frame 10 and the magazines thereon under the action of the eccentrics, the cam 34 rotates, and owing to the shape of this cam it causes the rod 33 resting thereon to ascend, the forward end of the frame 10 to which said rod is attached also ascending, this ascent continuing until the handle 36 reaches the position shown in Fig. 2, at which time the lower magazine will occupy the operative level shown in Fig. 2. During the latter part of the rotation of the shaft 35, the eccentrics return to their forward positions, thus shifting the frame 10 and hence the magazines thereon forward, the escapements on the lower magazine being brought into operative position above the actuating reeds and the lower stop or seat 16 being brought into engagement with the stationary part 17 of the frame. The lower magazine is shifted out of operative position and the upper magazine brought into position for use by a reversal of the motion of the crank or handle 36, the forward end of the frame 10 and the forward ends of the magazines thereon being lowered, during which movement the frame 10 and the magazines thereon are

bodily shifted first rearwardly and then forwardly, as before, to withdraw the escapements of the lower magazine from the reeds and to engage the escapements of the upper magazine with the reeds. If desired, an additional cam 39^a, larger than the cam 34, may be provided on the shaft 35 for the purpose of elevating the frame 10 to a height sufficient to enable the lower magazine M' 10 to be removed forwardly above the assembler chute 3, as shown in Fig. 5. This cam 39^a is loosely hung on the shaft 35 and it normally occupies the pendant position shown in Figs. 1 and 2, but by shifting this 15 cam along the shaft 35, a key-way in its hub is engaged with a key 40 fixed to the shaft 35, the cam 39^a being thereby coupled to said shaft, and rotation of the shaft will cause the cam 39^a to operate upon the cross-bar 33 of the frame 10, thereby elevating the forward end of this frame to the height shown in Fig. 5.

The matrix conveyer screws of the upper and lower distributers may be driven in any 25 suitable way. As shown, belts 41 and 42 extend from belt pulleys on a driving shaft 43 to driving pulleys on the respective screws, these belts being sufficiently slack or elastic to permit shifting movements of 30 the distributers to take place incidental to the shifting of the magazines without interrupting the operation of the distributers.

During either of the magazine-changing operations above described, the upper and 35 lower distributers, distributer boxes and the channel entrances remain in fixed relation with the respective magazines by virtue of the mounting of these parts in fixed positions on the magazine-carrying frame 10, and 40 hence distribution of matrices to either or both magazines may continue without interruption while the magazine shifting operation is being performed and also after the shift has been made, in consequence of which 45 changing of the magazines may be effected immediately and at the moment desired without awaiting the return of matrices belonging to the magazine previously in use.

I claim as my invention:

50 1. In a typographical machine, a main frame, a frame carrying a plurality of matrix magazines and shiftable relatively to the main frame to bring one or another of the magazines thereon into position for use, and primary matrix separating mechanism and also matrix distributing mechanism for said magazines mounted on said shiftable frame and adapted to maintain operative relation with each other and with 55 said magazines during shifting of said frame.

2. In a typographical machine, a main frame, a plural magazine frame shiftable relatively to the main frame to bring one or 60 another of the magazines thereon into po-

sition for use, distributers for the respective magazines movable bodily with said magazine frame to maintain operative relations with such magazines during shifting of the magazine frame, and a primary distributer for separating matrices belonging to different magazines, said primary distributer being carried by said shiftable magazine frame and adapted to remain in fixed relation with the distributers for the 70 respective magazines. 75

3. In a typographical machine, a main frame, a magazine frame having a plurality of magazines mounted in fixed position thereon, said magazine frame and the magazines thereon being shiftable to bring one or another of such magazines into position for use, primary matrix separating means and distributing mechanisms mounted in fixed relation with said magazine frame and the 80 magazines thereon and adapted to remain in fixed operative relation with the magazines and the primary matrix separating means during shifting of the magazines. 85

4. In a typographical machine, a main 90 frame, a magazine frame having a plurality of magazines mounted thereon, distributers mounted on said magazine frame and individual to the respective magazines thereon, channel entrances between the distributers and the respective magazines and a primary distributer for separating the matrices belonging to different magazines, the magazine frame and the magazines, primary distributer and individual distributers and 95 channel entrances being bodily shiftable relatively to the main frame to bring one or another of the magazines into position for use. 100

5. In a typographical machine, a main 105 frame, a magazine frame having a plurality of magazines thereon, distributers on the magazine frame individual to the respective magazines, a primary distributer box common to said distributers, and means for 110 separating the matrices belonging to the different magazines, said magazine frame and the distributers, distributer box and matrix separating means being bodily shiftable as a unit relatively to the main frame when 115 one or another of the magazines is brought into position for use.

6. In a typographical machine, a main frame, a magazine frame having a plurality of magazines mounted in superposed relation thereon, means for raising or lowering the forward matrix-delivery ends of the magazines to bring the same to their respective operative levels, and means pivotally engaging and supporting the upper portion 125 of the magazine frame and operative to shift the magazine frame and the magazines thereon rearwardly and then forwardly concurrently with said raising or lowering movement. 130

7. In a typographical machine, a main frame adapted to support escapement-actuating means, a magazine frame having means for mounting a plurality of magazines in superposed relation thereon, means including a cam operative upon the magazine frame to raise or lower the forward matrix-delivery ends of the magazines to bring the latter to their different operative levels relatively to the escapement-actuating means, and means including an eccentric engaging and thereby supporting the upper portion of the magazine frame and operative to shift said magazine frame and the magazines thereon rearwardly and forwardly relatively to said escapement-actuating means during said raising or lowering movement.

8. In a typographical machine, a main frame, a magazine frame adapted to support and carry a plurality of magazines in superposed relation thereon, means including a cam on which the forward portion of the magazine frame rests, said cam being operative to raise or lower the forward matrix-delivery ends of the magazines, and means including a shaft operatively connected to said cam and having eccentrics operative upon the magazine frame to support the same and to shift said frame and the magazines thereon rearwardly and forwardly during the raising and lowering movements of the forward ends of the magazines.

9. In a typographical machine, a main frame having matrix-delivery mechanism thereon, a magazine frame adapted to re-

movably support a plurality of magazines in superposed relation thereon, means for shifting the magazine frame relatively to the main frame to bring one or another of the magazines thereon into operative relation with said delivery mechanism, and means operative independently of the magazine shifting means for shifting the magazine frame into a further position to elevate the lowermost magazine thereon above the delivery mechanism and thus enable removal of such magazine from the magazine frame.

10. In a typographical machine, a main frame having matrix-delivery mechanism thereon, a magazine frame adapted to removably support a plurality of magazines in superposed relation thereon, means including a rotatable shaft and a cam thereon for shifting the magazine frame to bring one or another of the magazines thereon into operative relation with said delivery mechanism, and a second cam on said shaft normally loose thereon and capable of being connected therewith whereby rotation of said shaft while the second cam is connected thereto will elevate the lowermost magazine above the delivery mechanism and thus enable removal of such lowermost magazine from the magazine frame.

In testimony whereof I have hereunto set my hand in presence of two subscribing witnesses.

THOMAS W. JOHNS.
